UNITED STATES PATENT OFFICE

WILLIAM HENRY TICE, OF PORTLAND, OREGON, ASSIGNOR TO TICE LOCK WASHER MANUFACTURING COMPANY, OF PORTLAND, OREGON, A CORPORATION OF OREGON

PROGRESSIVE DIE FOR MANUFACTURING LOCK WASHERS

Application filed October 1, 1929. Serial No. 396,432.

My invention relates to a punch and die for the manufacture of lock washers. The device in its preferred embodiment consists primarily of a base die and a punch holder adapted for use in a punch press for the mass production of lock washers. In the die holder or base is formed the essential elements for the forming, shaping and completing of the lock washer and in the punch holder is placed the essential elements for engagement with the die and for the cutting and punching of the central hole, the forming of the body element into shape and the final cutting of the finished product from the sheet from which the lock washer is being formed.

The object of my invention is to manufacture lock washers from sheet stock for mass production.

A further object of my invention consists in providing a progressive die so constructed that when the same is placed in a punch press that the same will form a completed lock washer at each cycle of the punch press by the progressing of the stock from which the lock washer is made through the punch press.

A further object of my invention consists in providing a progressive die for the forming of lock washers from sheet stock and wherein the essential elements for forming the lock washer may be removed and replaced from the die to maintain the die in a high working efficiency.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a perspective, top, plan view of the base of the die in which the various forms are sunk.

Fig. 2 is a front view of the assembled punch and form holder, the same being shown in assembled position.

Fig. 3 is an end view, partially in section, of the mechanism illustrated in Fig. 4.

Fig. 4 is a sectional, end view, of the assembled die, the same being taken on line 4-4 of Fig. 2 looking in the direction indicated.

Fig. 5 is a fragmentary, sectional, end view of the mechanism illustrated in Fig. 2, the same being taken on line 5-5 of Fig. 2 looking in the direction indicated.

Fig. 6 is a fragmentary, sectional, side view of the jaw forming portion of the die, the same being taken on line 6-6 of Fig. 5 looking in the direction indicated.

Fig. 7 is a top, plan view of the stock from which the lock washer is made and illustrating the same in condition for the progressive manufacture of lock washers.

Fig. 8 is a perspective, plan view of the washer to be made within the die.

Fig. 9 is a perspective view of the punch holder illustrating the various elements for forming the lock washer in position within the holder.

Fig. 10 is a sectional, front view of the assembled device, illustrating the stock from which the lock washer is to be made in place within the die.

Fig. 11 is a sectional, plan view of the assembled device, the same being taken on line 11-11 of Fig. 10 looking in the direction indicated.

Like reference characters refer to like parts throughout the several views.

My new and improved invention is for the purpose of making lock washers as illustrated in Fig. 8 wherein the lock washer is made from sheet stock of uniform thickness. The washer has a body portion 1 and in the initial forming of the washer a triangular shaped piece 2 is removed from the body portion of the washer. In the next operation slits 3 and 4 are formed adjacent each side of the triangular portion for a substantial distance at each side of the triangular slit and jaws 5 and 6 are then formed from the body portion and offset to form cutting points 7 and 8. In the initial step in the forming of the washer the central hole 9 is removed from the strip 10 from which the washer is to be formed and the stock and the triangular piece 2 are simulta-

neously removed from the sheet stock as illustrated within the dotted lines at 11 in Fig. 7. The sheet stock from which the lock washer is to be made is then progressed the width 5 of one washer and the slits 3 and 4 are formed in the next progression. The locking jaws 5 and 6 are then formed at offsets to the plane of the body element in the next progression and the locking jaws are swedged 10 uniformly therewith to a uniform taper and in the final progression of the sheet stock the lock washer is cut from the sheet stock.

The progression of the sheet stock within the die is illustrated in Figs. 10 and 11 and 15 in Fig. 11 the punch for forming the central hole is illustrated at 12 and the punch for cutting out the front side of the washer and the triangular notch is illustrated at 13. The punch for removing the finished washer in 20 the final progression operation is illustrated at 14. The base of the die holder is best shown at 15 and the punch holder is illustrated at 16 in Figs. 1 and 9 respectively. The punch 12 for forming the central hole 25 within the body portion of the lock washer is shown within the punch holder in Fig. 9 and the punch 13 for cutting out the front portion of the washer and for forming the triangular notch of the body portion is also 30 shown in Fig. 9. The locator punch 17 is shown with its holder 18. The holder 18 has a face 19 for forming the jaw portion of the lock washer in precise alignment and thickness. In the next progression of the 35 stock 10 from which the lock washer is being formed, the swedging punch 20, having the jaw forming faces 21 and 22, slits the jaws from the body portion and inclines the jaws at an angle, and bends the free ends without 40 the plane of the body portion of the body of the lock washer. In the last progression of the stock the punch 14 cuts the washer from the stock as a finished product. A plate 23 is placed within the die holder and 45 the inner edge 24 of the same is slightly tapered in order to emboss the jaws of the lock washer and form the same slightly tapering in cross sectional area in order to form the locking jaws of the washer slightly 50 thinner on their inner edges than on the outer edge of the jaw in order that the nut, when tightened upon the bolt in which the lock washer is being used, may not engage the locking jaws themselves upon the slit side 55 of the locking jaw.

While the form of mechanism herein shown and described is admirably adapted to fulfill the objects primarily stated, it is to 60 be understood that it is not intended to confine the invention to the one form of embodiment herein shown and described, as it is susceptible of embodiment in various forms, all coming within the scope of the claim 65 which follows.

What I claim is:

In a device of the class described, the combination of a punch and die holder adapted for companion use in a punch press, a bolt hole punch and a shearing punch having a triangular projection outwardly extending therefrom carried by the punch holder arranged to function as the initial operation and adapted to form a V-shaped notch in the blank being punched, a locator point and a swaging plate arranged in spaced relation with the initial punches and adapted to make a tongue forming slit at each side of the V-shaped notch, a shearing and forming punch arranged in spaced relation with the locator point and adapted to bend each of the tongues out of the plane of and upon the oppositely disposed sides of the body of the blank being punched, a shearing punch for the removal of the finished product arranged in spaced relation with the shearing and forming punch and receiving openings disposed within the die holder and in registerable alignment with the punching, shearing and locator elements disposed in the punch holder.

WILLIAM HENRY TICE.
